CLAIM

The ornamental design for a batten arrangement for building surfaces, as shown and described.

DESCRIPTION

FIG. 1 is a top plan view of a batten arrangement for building surfaces, in a deployed configuration.

FIG. 2 is a bottom plan view of FIG. 1.

FIG. 3 is a side view that illustrates the batten arrangement of FIG. 1 in an undeployed configuration, viewed in the plane of FIG. 1 and from the right end, perpendicular to the battens illustrated the batten arrangement.

FIG. 4 is a latitudinal side view of FIG. 1; and,

FIG. 5 is a top perspective view of FIG. 1.
